LOADING APPARATUS.
APPLICATION FILED SEPT. 11, 1907.

3 SHEETS—SHEET 3.

UNITED STATES PATENT OFFICE.

JOHN COLLINS, OF DAYTON, OHIO.

LOADING APPARATUS.

No. 872,901.

Specification of Letters Patent.

Patented Dec. 3, 1907.

Application filed September 11, 1907. Serial No. 392,332.

To all whom it may concern:

Be it known that I, JOHN COLLINS, a citizen of the United States, residing at Dayton, in the county of Montgomery and State of Ohio, have invented certain new and useful Improvements in Loading Apparatus; and I do hereby declare the following to be a full, clear, and exact description of the invention, such as will enable others skilled in the art to 10 which it appertains to make and use the same.

My invention consists in the novel features hereinafter described, reference being had to the accompanying drawings which illustrate 15 one form in which I have contemplated embodying my invention and said invention is fully disclosed, in the following description and claims.

Referring to the said drawings, Figure 1 is 20 a side elevation of an apparatus embodying my invention. Fig. 2 is an end view of the same. Fig. 3 is a top plan view of the apparatus. Fig. 4 is a longitudinal vertical sectional view of the same. Fig. 5 is a trans- 25 verse vertical sectional view of the machine, on line 5—5 of Fig. 1.

The object of my invention is to provide an apparatus for removing loose material and discharging the same, and is particularly de- 30 signed for removing mined coal or ore in a mine, and for discharging it into cars or other devices for facilitating its removal from the mine. The apparatus is, however, applicable to other uses.

My invention consists of a vehicle which is 35 preferably provided with a motor for operating the various parts of the mechanism as hereinafter described and also for propelling the vehicle forward or backward, and capa- 40 ble of being steered by the operator. I do not, however, limit myself to a motor pro- pelled and operated apparatus as the operating parts may be driven by hand if desired and the apparatus may be propelled in other 45 ways. Upon the vehicle frame is mounted a conveyer, disposed in a substantially horizontal or horizontally inclined position and being preferably an endless conveyer such as a belt reinforced by transverse slats, or other- 50 wise constructed. In advance of the forward end of the conveyer is arranged a pivoted scoop, the bottom of which is closely adjacent to the ground and which can be run or forced beneath a portion of the material to be removed, by advancing the vehicle.

Mechanism is provided for tilting or tipping the scoop, preferably by rocking it rearward, so as to discharge its contents upon the conveyer, and I prefer to provide operative connections between the scoop and conveyer so 60 that the upper section of the latter will be operated in a rearward direction as the scoop is tilted. The conveyer is also provided with mechanism for operating it independently of the scoop, so that the material dumped thereon can be moved rearward far enough so that it will not fall off into the scoop and to provide space for the next scoop full, and also for operating the conveyer to run off and discharge the contents thereof when it is fully 70 loaded, and the vehicle has been moved into which the contents of the conveyer is to be discharged. I also provide the conveyer with adjusting mechanism for its rear or discharge end to enable the same to be raised or lowered to facilitate delivery to a car or other apparatus, when desired.

In the form of my invention shown in the accompanying drawings A represents the frame of a supporting vehicle which is sup- 80 ported upon the traction wheels a a and steering wheel a'.

B represents the frame of an endless conveyer pivotally mounted at the forward end of the frame A, upon shaft b and extending 85 rearwardly preferably beyond the rear end of the vehicle. The shaft b is provided with a drum b' and the rear end of the frame is provided with a roller b² and upon said drum and roller is mounted the endless conveyer 90 B' of any desired construction. The rear end of the conveyer frame is supported ad- justably so that it can be raised or lowered and held in its adjusted position. In this instance I have shown the vehicle frame pro- 95 vided on opposite sides with toothed seg- ments or racks b³ and the frame B provided with weighted pawls b⁴ to engage said racks, and hold the frame in its adjusted position. The frame B can be raised and lowered by 100 means of a windlass b⁵ and flexible connec- tions b⁶ b⁷ extending therefrom to the conveyer frame, the said windlass being oper- ated either by hand, as by crank b⁷, or the windlass may be connected with the motor 105 if desired.

In advance of the forward end of the conveyer B' is a pivoted scoop C, which is pref- erably pivoted to the shaft B, as shown. The scoop consists of bottom and sides and is 110

preferably open at the rear to facilitate dumping its contents rearward upon the conveyer B.

Upon the main frame A and supported in suitable bearings is a crank shaft D, extending across the machine and provided with cranks d, which are connected by links d' with the scoop C above its pivotal connections for dumping the scoop as indicated in dotted lines Fig. 1. I do not, however, limit myself to this exact mechanism for elevating and dumping the scoop as the same may be modified considerably without departing from my invention. I also provide means for operating the elevator from the scoop, when the latter is being raised to discharge its contents, which consists in this instance of ratchet wheels c c secured upon shaft b of the drum, and pawls c' c' pivoted upon the sides of the scoop and engaging said ratchet wheels in such manner that as the scoop is raised the drum will be rotated and the conveyer moved with the scoop, thus preventing the material in the scoop from rubbing and abrading the adjacent portions of the conveyer and also moving any material previously deposited on the conveyer further along to facilitate the dumping of the load in the scoop.

The vehicle frame A is preferably provided with a suitable motor indicated at M, which may be a steam or explosive engine or an electric motor operated by storage battery or from a distant source of power through a trailing wire, or other desired form of motor. The main shaft m of the motor is operatively connected with the traction wheels a a in any desired manner for operating the vehicle forward or backward. In this instance I have shown said shaft connected by sprocket chain m' to a counter shaft m², provided with the usual differential gear and clutch mechanism, not shown, said shaft m² being connected by sprocket chains m³ to the traction wheels in a well known manner. I have also indicated a clutch lever m⁴ for operating the machine forward or rearward by corresponding movements of the lever. Any usual or preferred connections may be employed for transmitting the power of the motor to the traction wheels.

I also provide independent mechanism for connecting the motor, when desired to the drum shaft b, and to the crank shaft D. In this instance I have shown a second counter shaft E mounted on the frame A and connected with the motor shaft m by sprocket chain m⁵. The counter shaft, is also provided with loosely mounted sprocket wheel e connected by chain e' to a sprocket e¹ on the drum shaft b, and said counter shaft E is also provided with a sprocket wheel e² loosely mounted thereon and connected by chain e⁴ with the sprocket wheel e³ on crank shaft D. Suitable clutches e⁶ e⁷ are provided

on shaft E for throwing the loose wheels e and e³ into connection with the shaft, the clutch e⁶ being operated by a hand lever F and the clutch e⁷ being operated by foot lever G.

I also prefer to provide the frame A with a seat H for the driver or operator as shown within convenient reach of the various operating levers, and of a steering shaft S which is operatively connected with the steering wheel a' in any desired manner, in this instance by means of a crank s and steering link s'.

What I claim and desire to secure by Letters Patent is:—

1. The combination with a vehicle, of an endless conveyer mounted thereon, a pivotally mounted scoop, located in advance of and adjacent to the said conveyer, and means for tipping said scoop rearward upon its pivotal connections to discharge its contents upon said conveyer, substantially as described.
2. The combination with a vehicle, of an endless conveyer mounted thereon, a scoop pivotally mounted in advance of and adjacent to said conveyer, mechanism for tipping said scoop on its pivotal connections to discharge its contents upon said conveyer and operative connections between said scoop and conveyer for operating the conveyer when the scoop is tipped, substantially as described.
3. The combination with a vehicle, of an endless conveyer mounted thereon, a scoop pivotally mounted in advance of and adjacent to said conveyer, mechanism for tipping said scoop on its pivotal connections to discharge its contents upon said conveyer, operative connections between said scoop and conveyer for operating the conveyer when the scoop is tipped, and mechanism for operating said conveyer independently of said scoop, substantially as described.
4. The combination with a vehicle, of an endless conveyer mounted thereon, a pivotally mounted scoop located in advance of said conveyer, mechanism for tipping said scoop upon its pivotal connections to discharge its contents upon said conveyer, and means for raising and lowering the discharge end of said conveyer, substantially as described.
5. The combination with a vehicle, of an endless conveyer mounted thereon, a pivotally mounted scoop located in advance of one end of said conveyer, a motor mounted on said vehicle, operative connections between said motor and said scoop for tipping the scoop rearward on its pivotal connections to discharge its contents upon said conveyer, and connections between said motor and said conveyer for operating the latter, substantially as described.
6. The combination with a vehicle, of an

endless conveyer mounted thereon, a pivotally mounted scoop located in advance of one end of said conveyer, a motor mounted on said vehicle, operative connections between said motor and said scoop for tipping the scoop rearward on its pivotal connections to discharge its contents upon said conveyer, operative connections between said scoop and said conveyer for operating the conveyer when the scoop is tipped, independent connections between said motor and said conveyer, for operating the latter independently of said scoop, substantially as described.

15 7. The combination with a vehicle, of an endless conveyer mounted thereon, a scoop pivotally supported in advance of and adjacent to one end of said conveyer, a motor mounted on said vehicle, operative connec-

tions between the motor and supporting 20 wheels of the vehicle for moving the vehicle, operative connections between the motor and said scoop for tipping the scoop to discharge its contents on the conveyer, operative connections between the scoop and said 25 conveyer for operating the conveyer when the scoop is tipped, operative connections between said motor and said conveyer for operating the conveyer independently of said scoop and means for raising and lowering the 30 delivery end of said conveyer, substantially as described.

In testimony whereof I affix my signature, in the presence of two witnesses.

JOHN COLLINS.
